UNITED STATES PATENT OFFICE.

GEORGE H. WHEARY, OF RACINE, WISCONSIN, ASSIGNOR TO THE HARTMANN TRUNK COMPANY, OF RACINE, WISCONSIN.

TRUNK.

No. 879,074.

Specification of Letters Patent.

Patented Feb. 11, 1908.

Application filed August 7, 1907. Serial No. 387,526.

To all whom it may concern:

Be it known that I, GEORGE H. WHEARY, a citizen of the United States, residing at Racine, in the county of Racine and State of Wisconsin, have invented a new and useful Trunk, of which the following is a specification.

This invention relates to devices of that class known as wardrobe trunks, and has for its principal object to provide a novel construction of trunk in which clothing may be properly packed and held in shape while traveling.

A further object of the invention is to provide a trunk of such nature that ready access may be had to any article within the trunk without unpacking or removing the rest of the contents.

A still further object of the invention is to provide a wardrobe trunk in which the clothes carrier proper may be bodily removed from the trunk if necessary and used in the boudoir as a bureau or chiffonnier.

A still further object of the invention is to provide a clothes carrier, that is so mounted as to be readily slid into and out of the trunk proper, while the trunk is on end, and further to provide a trunk with a foldable track-way which may be turned up to permit closing and locking of the trunk after the clothes carrier has been moved back.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a perspective view of a wardrobe trunk constructed in accordance with the invention, showing the trunk open and the clothes carrier and container withdrawn. Fig. 2 is a transverse sectional view through the body portion and lid of the trunk in closed position. Fig. 3 is a sectional view taken in a plane at right angles to Fig. 2, and illustrating the movable clothes carrier.

Similar numerals of reference are employed

to indicate corresponding parts throughout the several figures of the drawings.

The trunk or containing box 10 may be of any preferred construction, and of any size, and is provided with a lid or cover which may be provided with the usual locks or other fastenings.

As the device is intended to be stood on one end during transportation and when in use, the upper end is provided with a rounded projection 12 which will prevent the retention of the trunk with this end as a base, and this upper end is furthermore provided with a handle 13, while the opposite end is left without a handle, or one may be added if desired.

Fitting within the lower end of the trunk is a plate 15, the front edge of which projects beyond the edge of the trunk or box proper and extends partly into the lid, and to the forward edge of this plate is pivoted a second plate or track way 16 which is pulled up to an approximately vertical position when the trunk is closed, and which may be allowed to drop to a horizontal position in order to form an extended platform or trackway on which the clothes container or wardrobe proper may be slid into and from the trunk.

In order to maintain the extension track-way 16 in a horizontal position, its forward end is provided with a pivoted flap 17 which is connected to the under side of the track-way 16 by a spring or springs 18 which tend to move the flap down to a position at a right angle to the general plane of the trackway, and thus form a supporting foot that will rest on the floor and maintain the upper surface of the trackway in alignment with the upper surface of the plate 15.

When the auxiliary or track extension 16 is moved up to the vertical position, the flap 17 is turned up to a position in alignment with the extension 16, and is held by means of a catch 19 that preferably is in the form of a strap of leather or other flexible material having a socket member to receive a button 100 or stud on the flap. This is simply for the purpose of flattening the flap, so that its extra height will not prevent closing of the lid.

The clothes container or wardrobe proper is in the form of a rectangular box or casing 20 having a top 21, end panels 22, and a solid back 23, and extending from the lower portion of the back is a tray 25 having a solid

bottom, the tray being arranged for the reception of any articles and serving especially to hold the lower portions of any garments which may be hung on the clothes supports that are arranged above the tray.

To the upper portion of the casing 21 is secured a U-shaped frame 26, the inner ends of the side arms of which are riveted or otherwise permanently secured to the upper portions of the side panels of the casing, and these side arms are reinforced by angle bars 27 that are riveted to the side arms and to the back of the casing. The frame is further strengthened by the employment of a pair of parallel rods 28 that extend from the outer wall of the frame to the angle bars or brackets 27.

Mounted to slide on the rods 28 are bars 30, preferably formed of wood and provided with small notches 31 which receive the upper portions of the rods and serve to prevent accidental displacement. Each of these bars is provided with a centrally disposed metallic hook 31 on which is hung a supporting hook 32 of a garment supporter 33, the latter being of any preferred construction, and generally of that type arranged to receive an upper garment, such as a coat or waist, although trousers and skirt hangers may be employed when desired.

In practice, there are as many garment supporters as may be necessary to fill the space and accommodate the clothing, and after the garments have been hung a clamping frame 34 is employed to hold them in position. This clamping frame comprises a pair of vertical bars 35 the upper portions of which are provided with side notches 36 to receive the rods 28 and the bars are connected by cross strips 37 arranged at suitable intervals. This frame is placed in position against the outermost garment, and is then forced back and tied in place by tapes or cords 39, the ends of which are secured to the back of the casing 20, so that the garments will be properly held in place even where the trunk is turned upside-down or otherwise badly handled.

The casing 22 is reinforced by a transversely disposed plate 41 which, also, forms a slide for the reception of a drawer 42. At points above and below the plate 41 are arranged angle bars 43 that are secured to the inner surface of the end walls 22 and form supports for additional drawers 44, all of which are accessible from the front of the casing 20. These drawers may be arranged to contain clothing or other articles, and the drawers are held in closed position by one of the walls of the trunk or box, so that they cannot fall out during transit.

The casing as a whole is mounted on two pairs of rollers or casters 46 which run on the plate 15 and track section 16, and secured to the bottom of the casing is a pair of flanged

guide bars 48 that are arranged to engage with a similar pair of flanged guide bars 49 that are carried by the track extension 16, these guide bars serving to prevent any lateral displacement of the casing during movement of the latter into and from the trunk proper, although, if desired, the casing as a whole may be drawn out until it is beyond the track extension 16 and rests on the floor of the room where the casing may then be utilized as a wardrobe or chiffonnier while the trunk or box proper may be removed or used for containing other articles. In order to facilitate the movement of the casing, one of the end panels 22 is provided with a suitable operating handle 51.

I claim:

1. In a wardrobe trunk, a box or casing, a lid or cover connected thereto, a supporting plate secured to one end of the casing, an extension track pivoted to the forward end of the plate, an auxiliary means for supporting the outer end of the track in a horizontal position, and a movable casing or wardrobe support on said plate and track and movable into and from the box.

2. In a wardrobe trunk, a containing box, a cover therefor, a wheeled clothes carrier mounted within the box, a pivoted extension track way adjustable to horizontal position and forming a support for the carrier as the latter is withdrawn from the box, said track-way being foldable within the box to permit the cover of the latter to close, and interengaging guides between the clothes carrier and track-way to prevent lateral displacement of said carrier.

3. In a wardrobe trunk, a containing box, a lid or cover therefor, a wheeled casing mounted within the box, a pivoted extension track way adjustable to horizontal position and forming a support for the casing as the latter is withdrawn from the box, an auxiliary flap carried by the extension and serving to support the latter in horizontal position, and interengaging guides between the casing and the track way to prevent lateral displacement of said casing.

4. In a wardrobe trunk, a containing box, a lid or cover therefor, an extension track-way pivoted and movable from an approximately vertical to approximately horizontal position, a pivoted flap on said track extension, springs tending to move the flap to supporting position, a casing movable into and from the containing box, and supported by the extension track during such movement, and means on the casing for holding the flap in alignment with the track extension when the latter is folded to vertical position.

5. In a wardrobe trunk, a containing box, a lid or cover therefor, an extension track-way pivoted to one end of the box, a casing mounted within the box and provided with flanged guides, a pair of flanged bars on the

track extension coacting with said flanged guides to prevent shifting of the casing, and supporting rollers for said casing.

6. In a wardrobe trunk, a containing box,
5 a cover therefor, a plate secured to the lower end of the box and extending beyond the edge thereof, an extension track pivoted to the end of the plate, a casing having rollers arranged to move on the plate and track, in-
10 terfiting flanged bars carried by the extension track, and bottom of the casing, a series of drawers arranged within said casing, a U-shaped frame secured to and projecting from the back of the casing, angle bars forming
15 supports for the frame, a pair of parallel rods

extending from the frame to the angle bars, garment supporters hung on the rods, a garment clamping frame, flexible connecting means extending from the back of the frame and holding the garment clamped in position, 20 and a tray extending from the lower rear portion of such frame below the garment supporter, substantially as specified.

In testimony that I claim the foregoing as my own, I have hereto affixed my signature 25 in the presence of two witnesses.

GEO. H. WHEARY.
